HYGROMETER

Hamilton R. Bristol, Naugatuck, Conn., assignor
to The Bristol Company, Waterbury, Conn., a
corporation of Connecticut

Application January 26, 1933, Serial No. 653,614

6 Claims. (CL 73—24)

The invention relates to measuring apparatus, more especially as utilized in the determination of relative humidity.

It has for an object the provision of a simple and rugged precision instrument embodying a member of hygroscopic material whose changes in physical dimensions are indicative of the relative humidity conditions of the ambient atmosphere.

10 It has for a further object the provision therein of a natural fibrous organic material possessing the required capillary structure for absorbing the moisture to which it may be exposed, said material being mounted for intimate contact between its 15 fibres and the ambient atmosphere whereby response of the member is rapid and definite.

Still another object of the invention resides in the arrangement of such material in an instrument in a manner to obviate distortion or irregular bending such as warping, buckling or twisting thereof, the member being free to bow uniformly.

20 A further object of the invention is to provide a responsive element of this nature which shall also have sufficient strength to insure a positive indication by providing a relatively great force when exposed to humidity changes in the ambient atmosphere.

25 Still another object of the invention resides in the provision of a hygrometer which shall be relatively inexpensive to manufacture, efficient in operation, readily installed, and durable and reliable in service.

30 In carrying out the invention, the hygroscopic member is arranged to be initially constrained to an arched conformation as by being pivotally attached at its opposite ends to a rigid non-hygroscopic frame or block and arched or bowed between movable abutments provided thereon. Means are secured to the apex of the arch for transmitting to a suitable measuring element the effect of elongation or contraction of the member under humidity variations of the surrounding atmosphere.

45 As a particularly desirable hygroscopic member, a strip of wood is utilized, the same being relatively thin and so disposed that its fibres lie substantially parallel to its shortest dimension.

The nature of the invention, however, will best 50 be understood when described in connection with the accompanying drawing, in which:

Fig. 1 is a front elevation, with parts in vertical section, of a hygrometer embodying the invention, and with the surrounding casing removed.

55 Fig. 2 is a transverse vertical section thereof

taken on the line 2—2, Fig. 1 of the drawing, and looking in the direction of the arrows.

Fig. 3 is a plan view of the hygrometer.

Fig. 4 is an enlarged detail section through the hygroscopic member and taken on the line 4—4, 60 Fig. 3 of the drawing.

Referring to the drawing, 10 designates a suitable plate or support member for the novel mechanism, and a bracket 11 secured to the face of this plate is designed to support a block or carrying 65 device 12 of non-hygroscopic material and adapted to afford a rigid support for a hygroscopically-responsive element 13. The latter is arranged to be pivotally attached to opposite ends of the block 12 and in arched conformation, this being 70 effected by mounting the opposite ends of the element 13 in respective pivot blocks 14 and 15 which are carried by pairs of pivot screws 16 and 17, respectively, mounted in pairs of lugs 18 and 19 extending upwardly from the said block. The 75 strip 13 therefore has a substantially frictionless bearing at the abutments thus provided, and will alter its curvature in accordance with the varying conditions of humidity of the atmosphere surrounding it, as hereinafter set forth.

80 The said member 13 constituting the hygroscopically-responsive element is composed of straight-grained wood, which has first been freed from sap and other objectionable substances, as by alternately immersing the same in a solvent 85 and boiling, and then drying. The wood may thereafter be subjected to a process of compression, and finally is cut across the grain in such a manner that its natural fibres 13' are substantially parallel to the shortest dimension of the 90 strip which is of a thickness not exceeding 0.05 of an inch.

95 It is further desirable that the center line of the strip be parallel or perpendicular to the radius of the growth rings of the original lumber, in order that the elements of these rings may be symmetrically disposed in the finished strip and thus minimize a tendency to warp and twist with changes in moisture content. The strip, furthermore, may be provided with a central opening 100 20 to afford a means of connection to measuring means hereinafter set forth. Also, the strip is so dimensioned that when attached to the pivot blocks as aforesaid the distance between the center line of these blocks is materially greater than 105 the distance between the center line of the pivot screws designed to carry the corresponding pivot blocks. In order to mount the strip in its bearings, it is given a curved or arched conformation until the chord of the arc so formed equals the 110

- distance between the center lines of the pivot screws which are then inserted to mount the strip to its carrying block. This will maintain therefore the curvilinear shape of the strip. 80
5. A link 21 is connected to the responsive element or strip 13 substantially midway thereof through the central opening 20, and said link is connected with the one arm 22 of a bell crank whose other arm 23 may constitute a measuring element or pointer. Under these conditions, arm 23 is designed to cooperate with a scale 24 fixed to the plate 10 and graduated in values representative of the curvature of the responsive hygroscopic element aforesaid. The bell crank may 85 be pivotally supported by a bracket 25 secured to the block 12, as shown.
- Upon being exposed to an atmosphere whose humidity it is desired to determine, the moisture of this atmosphere will cause the fibres of the strip 13 to swell in a transverse sense to a degree depending upon the relative humidity of the ambient atmosphere. As the fibres of this strip are relatively short and exposed at both ends to such atmosphere, the tendency will be toward 90 20 a rapid equalization of moisture conditions throughout the mass of the strip, and a proportionately quick response to changes in atmospheric humidity is attained. At the same time, since the fibres are disposed perpendicularly to 95 25 the width and to the length of the strip, the latter will not have a tendency to warp or buckle, the resulting tendency upon changes in the moisture content of the fibres being to produce a corresponding change in the linear dimension of the strip. Both ends of the strip being fixed, however, with respect to their linear spacing, the longitudinal response will take the form of a 100 30 change in curvature of the strip, which, in turn, varies the location of the middle portion in a direction substantially perpendicular to the chord of the arc of said strip. This movement is communicated through the link and bell crank aforesaid for measuring movement with reference to the scale 24 to afford thereby an indication of the 105 35 relative humidity of the atmosphere to which the strip 13 is exposed.
- I claim:
1. In a hygrometer: a rigid non-hygroscopic block, a hygroscopic member pivotally attached 110 40 at its opposite ends to the block and in arched conformation, and means rigidly secured to the hygroscopic member intermediate its ends and adapted to transmit the effect of elongation and 115 45 contraction of the member under humidity variations in its surrounding atmosphere.
2. In a hygrometer: a rigid non-hygroscopic block, a hygroscopic member pivotally attached at its opposite ends to the block and in arched conformation, and means rigidly secured to the hygroscopic member substantially at its apex intermediate its ends and adapted to transmit the effect of elongation and contraction of the member under humidity variations in its surrounding atmosphere. 85
3. In a hygrometer: a rigid non-hygroscopic block, a hygroscopic member pivotally attached at its opposite ends to the block and in arched conformation, means rigidly secured to the hygroscopic member intermediate its ends and adapted to transmit the effect of elongation and contraction of the member under humidity variations in its surrounding atmosphere, and measuring means associated with the transmitting 90 50 means. 95
4. In a hygrometer: an element responsive to variations in the humidity of the surrounding atmosphere and comprising a thin strip of fibrous material flexibly secured at its opposite ends, bowed and having its fibres lying substantially parallel to the shortest dimension of the element. 100
5. In a hygrometer: a rigid non-hygroscopic block, a hygroscopic member pivotally attached 105 55 at its opposite ends to the block and in arched conformation, both sides of the strip being exposed to the surrounding atmosphere and subject to humidity variations therein whereby the strip will elongate or contract in accordance with the variations, and means to measure the resultant change in the longitudinal dimensions of said strip. 110
6. A hygrometer unit, comprising a base plate, a rigid non-hygroscopic block, a bracket securing said block to the base plate, lugs extending outwardly from the block, pivot blocks mounted in the respective lugs, a bowed hygroscopically-responsive element secured at its opposite ends to the respective pivot blocks, a bracket secured to 115 60 the non-hygroscopic block, a bell crank pivotally mounted on said second-named bracket, a link connecting one arm of the bell crank to the hygroscopically-responsive element, and a scale secured to the base plate adapted to cooperate with the other arm of said bell crank. 120 125
